UNITED STATES PATENT OFFICE.

ARCHIE R. WOLFE, OF SUMMIT, NEW JERSEY.

RADIO OR RADIOPHONE RECEIVING SET DEMONSTRATOR.

Application filed February 23, 1926. Serial No. 90,224.

My invention relates to improvements in the design and equipment of stationary or rotary stands or pedestals of circular, square, octagonal or semicircular, semi-square, semi-octagonal or quarter-circular, quarter-square, quarter-octagonal or other similar shape, so that they are especially adapted to afford a means of supporting and displaying one or more loop aerials, one or more loudspeakers 10 and three or more radio or radiophone receiving sets, and of testing, operating or demonstrating any one of said three or more radio or radiophone receiving sets, one or more loops and one or more loudspeakers.

The objects of my invention are first, to provide a means of quickly and efficiently connecting electrically any one of three or more radio or radiophone receiving sets to one or more of the following: one or any 20 one of two or more aerials, one or any one of two or more loops, one grounded lead, one or any one of two or more filament current voltages, one or any one of two or more plate current voltages and one or any one 25 of two or more loudspeakers as may be required for the purposes of testing, operating or demonstrating said receiving sets; and at the same time, to have the respective leads so connecting each receiving set to 30 said aerial, loop, grounded lead, filament current voltage, plate current voltage and loudspeaker practically free of dead end or noncurrent carrying conductors and of practically the same length and ohmic resistance; second, to provide a means for controlling the multipole multibranch electric switch which connects any one of the said receiving sets to one or more of the said aerial, loop, grounded lead, filament voltage, 40 plate voltage and loudspeaker as may be required, from a point near to or within convenient reach of said receiving set; third, to design a stationary or rotary pedestal or stand which will safely support and most effectively display three or more radio or 45 radiophone receiving sets, one or more loops and one or more loudspeakers for purposes of test, operation or demonstration; fourth, to produce an apparatus readily designed 50 to afford a means of supporting, displaying and quickly testing, operating and demonstrating any number or all of three or more instruments or units requiring a source or sources of electric current for their test, 55 operation or demonstration; fifth, to pro-

duce an apparatus adapted to facilitate student instruction in the practical operation of radio or radiocompass receiving sets or other units requiring a source or sources of electric current for their operation. 60

I desire to state here that the multipole multibranch electric switch, for which my application for Letters Patent was executed February third, 1925, is a standard part of the equipment of the radio or radiophone 65 receiving set demonstrator.

One form of the invention, a square, double platform type of rotary pedestal, adapted to accommodate one or more loudspeakers and one or more loops on the elevated platform and eight radio or radiophone receiving sets or other units size 7" by 7" by 18" or smaller on the lower platform is illustrated in the accompanying drawings, in which Fig. 1, is a view of the entire apparatus on the approximate double scale 2 1/2 inches equal 1 foot for horizontal measurements and 1 1/2 inches equal 1 foot for vertical measurements; Fig. 2, is a sectional view of the entire apparatus on the broken line 2, 2, Fig. 1; Fig. 3, is a view looking down from perpendicularly above the center on to the top of the demonstrator with the elevated platform trap doors open, and the battery shelf and feed and cut out switch 70 and its connections removed, showing the multipole multibranch electric switch proportionately enlarged, its electrical connections to the unit binding post boards and the method of extended control of said switch 75 from without the platform elevation. 80

The batteries shown in Fig. 2, are merely for the purpose of illustration and form no part of this invention.

Similar numerals refer to similar parts 90 throughout the several views.

To the metal base 1, is secured the metal pipe shaft 2, to which is secured the metal bearing bushing 3, by means of the removable metal pin 4. 100

The wooden crown 5, is rigidly secured to the wooden body 6, which is adapted to rotate on shaft 2 by means of the metal supporting and pivot bearing 7, which is secured to said crown by wood screws, and by means of the balance bearing 8, which is secured to said body 6 with wood screws. 105

Through the hinged hand hole door 9, access is had to the bearings 7 and 8, and to other working parts within the body 6. 110

The ring 10, made of insulating material is secured to shaft 2 by machine screws and supports the metal collector ring 11, to which is connected the ground lead 12, and 5 on which bears the spring metal brush 13.

The metal brush holder 14, supports said brush 13, and is secured to the insulator 15, which is secured to an arm of bearing 8.

It is now readily perceived that the 10 ground lead is continued from the stator to the rotor part of the pedestal through the collector ring 11 and brush 13 to the brush holder 14.

The lower platform 16, made of wood, is 15 secured to the body 6 by means of angle irons and the braces 17, and is provided with a rib 18, to hold the receiving sets or other units on said platform. The wooden elevated platform 19, is supported by and 20 secured to the wooden platform elevation 20, which is secured to the said lower platform 16.

The elevated platform 19, is provided with first, a rib 21, which holds the loud- 25 speakers, loops or other instruments in place on said platform; second, the hinged trap doors 22, through which access is had to the main feed and cut out switch 23, batteries if used, removable wooden shelf 24, multipole 30 multibranch electric switch 25, the insulation unit binding post boards 26, insulation battery terminal boards 27, and all electrical connections within the platform elevation 20; third, the cross frame 28, which partly 35 supports the trap doors 22, and to which the aerial entering insulator 29, the loop jack 30, and the loudspeaker jack 31, are secured.

Eight insulation binding post boards 26, on each of which are mounted seventeen 40 metal binding posts 38, are secured with wood screws over slots in the platform elevation 20, at points around the inner surface of the latter, so that said binding posts 38, protrude about four fifths of the way 45 through said slots, making the former accessible from without said platform elevation.

The circuits are completed through the 50 demonstrator by the legs as follows: one leg from each the aerial insulator 29, ground connection brush holder 14, negative loop jack 30, positive loop jack 30, negative 1.5 volt filament current, positive 1.5 volt filament current, negative 4 volt filament current, positive 4 volt filament current, negative 6 volt filament current, positive 6 volt filament current, negative plate current, positive 22½ volt plate current, positive 45 volt plate current, positive 67½ volt plate current, positive 90 volt plate current, negative 60 loudspeaker jack 31 and positive loud- 65 speaker jack 31 connect to respective main distributing poles of the main feed and cut out switch 23, pass through the knife blades to the branch poles of said switch, thence to 65 respective main binding posts 32, through

70 permanent leads to respective main distributing poles 33, of the multipole multibranch electric switch 25; from which points said legs are connected to respective branch binding posts 34, of any one of the eight branchways 35, by moving the branch poles 36, of said branchway into contact with the main distributing poles 33, by means of mechanism provided in the switch 25 which is 75 operated by a simple manipulation of a respective extension control rod 37. From the binding posts 38, of each unit binding post board 26, the said legs of the circuits can be completed as required to the terminals of a respective radio receiver or other 80 unit, by flexible leads.

The latches 39, drop down and lock the extension control rods 37 in the open position, so that the latch nearest any one binding post board 26, must be lifted before the 85 binding posts 38 of said binding post board can be connected in circuit by operation of the multipole multibranch switch 25.

On the battery terminal board 27, are 90 mounted eight binding posts 41, to which the terminals of the storage plate and filament batteries, if used, can be connected from within and to which the terminals of the battery charging source of current can be conveniently connected from without the 95 platform elevation 20.

In installing the demonstrator, it is first placed in the desired location and the ground lead 12, is passed from underneath the base 1 out through the recess 40. The demonstrator is then secured with lag screws or bolts through holes in base 1, to the floor. The ground lead 12, is then run along the floor or through the floor and connected to the ground. The aerial lead-in, after passing through a lightning switch and arrester is brought down from vertically above the aerial insulator 29, to which it is connected by a flexible lead.

For testing operating or demonstrating 110 receiving sets, first, the plate and filament batteries, if used, are placed in the proper position within the platform elevation 20, and their terminals properly connected to the knife blade poles of the feed and cutout switch 23, and to the binding posts 41; second, the loops and loudspeakers to be 115 demonstrated are placed on the elevated platform 19, and their plugs inserted in the loop jack 30, and the loudspeaker jack 31, respectively as desired; third, each receiving set to be tested, operated or demonstrated is then placed on the lower platform 16, and their terminals properly connected to the metal binding posts 38, of a respective unit binding post board 26, by means of flexible leads, in the order and as shown marked on said binding post board by the following abbreviations of the legs of the circuits: A, G, neg. L, pos. L, neg. 1.5F, pos. 120 125 130

1.5F, neg. 4F, pos. 4F, neg. 6F, pos. 6F, neg. B, pos. 22½B, pos. 45B, pos. 67½B, pos. 90B, neg. S and pos. S respectively.

The demonstrator is now ready for operation and any one of the receiving sets can be connected to or disconnected from one or more of the following: aerial, loop, grounded lead, filament current voltage, plate current voltage and loud speaker as required for test, operation or demonstration by simply lifting the latch 40, and moving the extension control rods 37 nearest said receiving set, to the closed or open position respectively.

15 Any one of the loops and loudspeakers can be connected in circuit by connecting their plugs in their respective jacks as desired.

The selection of aerial or loop, filament current voltage, and plate current voltage for each particular receiving set as required for test, operation or demonstration is made by properly connecting its terminals by means of insulated flexible leads to the binding posts 38, of its respective binding post board 26.

The branch binding posts 34, of each branchway 35, are connected by insulated leads to respective binding posts 38, of a respective unit binding post board 26.

I claim:

1. In a stand for the demonstration of radio sets and the like, a base and an upright pedestal, a cylindrical body rotatably mounted upon the bearings upon the pedestal, a platform rigidly affixed to the cylindrical body, a cabinet mounted upon the platform with its sides at a distance within the periphery of the platform, the platform forming a shelf around the cabinet, compartments within the cabinet for the storage of batteries, a plurality of series of binding posts upon the cabinet, a loop jack within the cabinet, a loud speaker jack within the cabinet, a ground connection within the pedestal and a means for connecting the loop jack to one series of binding posts, for connecting the loud speaker jack to another series of binding posts, for connecting the ground connection to another series of binding posts, for connecting the batteries to another series of binding posts.

2. In a stand for the demonstration of radio sets and the like, a base and an upright pedestal, a cylindrical body rotatably mounted upon bearings upon the pedestal, a cabinet mounted upon the platform with its sides at a distance within the periphery of the platform, the platform forming a shelf around the cabinet, compartments within the cabinet for the storage of batteries, a plurality of series of binding posts upon the cabinet, a loop jack within the cabinet, a loud speaker jack within the cabinet, a ground

connection within the pedestal and a single means for connecting the loop jack to one series of binding posts, for connecting the loud speaker jack to another series of binding posts, for connecting the ground connection to another series of binding posts, for connecting the batteries to another series of binding posts, the means further constituting a means for shifting the connection of each individual unit within its individual series.

3. In a stand for the demonstration of radio sets and the like, a base and an upright pedestal, a cylindrical body rotatably mounted upon bearings upon the pedestal, a platform rigidly affixed to the cylindrical body, a cabinet mounted upon the platform with its sides at a distance within the periphery of the platform, the platform forming a shelf around the cabinet, compartments within the cabinet for the storage of batteries, a plurality of series of binding posts upon the cabinet, a loop jack within the cabinet, a loud speaker jack within the cabinet, a ground connection within the pedestal and a single means for connecting the loop jack to one series of binding posts, for connecting the loud speaker jack to another series of binding posts, for connecting the ground connection to another series of binding posts, for connecting the batteries to another series of binding posts, the means further constituting a means for shifting the connection of each individual unit within its individual series and consisting of a multipole multibranch electric switch.

4. In a stand for the demonstration of radio sets and the like, a base and an upright pedestal, a cylindrical body rotatably mounted upon bearings upon the pedestal, a platform rigidly affixed to the cylindrical body, a cabinet mounted upon the platform with its sides at a distance within the periphery of the platform, the platform forming a shelf around the cabinet, compartments within the cabinet for the storage of batteries, a plurality of series of binding posts upon the cabinet, a loop jack within the cabinet, a loud speaker jack within the cabinet, a ground connection within the pedestal and a single means for connecting the loop jack to one series of binding posts, for connecting the loud speaker jack to another series of binding posts, for connecting the ground connection to another series of binding posts, for connecting the batteries to another series of binding posts, the means further constituting a means for shifting the connection of each individual unit within its individual series and consisting of a multipole multibranch electric switch, and means upon the outside of the cabinet for operating the switch.
